UNITED STATES PATENT OFFICE.

GEORGE S. COLEMAN, OF NEW YORK, N. Y.

MOVING-PICTURE BASEBALL SCOREBOARD.

Application filed October 27, 1922. Serial No. 597,348.

To all whom it may concern:

Be it known that I, GEORGE S. COLEMAN, a citizen of the United States, residing at New York, in the county of New York and 5 State of New York, have invented certain new and useful Improvements in Moving-Picture Baseball Scoreboards, of which the following is a specification.

This invention relates to an apparatus for 10 reproducing baseball games by which the various plays made in an actual game may be shown as they occur.

The present invention has for a general object to provide an improved apparatus of 15 the type set forth.

A further object is to provide a novel and improved type of projection apparatus whereby pictures representing the players executing the plays, or executing any acts 20 incidental to the playing of the game or the actions of others such as umpires and coaches, also the flight of the ball as it is thrown or batted, may be shown on a board, screen, or other surface marked off to represent 25 a base-ball field.

A further object relates to the provision of means for projecting the representation of the ball in a manner to keep a proper focus as the ball is indicated on different 30 parts of the playing field which may vary in distance from the point of projection. Also to provide for maintaining the representation of the ball at the proper size as it is moved over the playing field.

35 Still another object relates to the provision of a novel and simple form of switchboard for controlling the current to the projection lamps.

For further comprehension of the invention, and of the objects and advantages thereof, reference will be had to the following description and accompanying drawings, and to the appended claims in which the various novel features of the invention are 45 more particularly set forth.

Fig. 1 of the drawings is a diagrammatic side view of the complete apparatus.

Fig. 2 is a face view showing the arrangement of the projectors on their supporting frame.

Fig. 3 is a face view of the board representing the playing field, and on which the pictures are projected.

Fig. 4 is a detail side view of one of the 55 projectors, showing its support in transverse cross section.

Fig. 5 is a detail plan view of the bracket or base of the projector.

Fig. 6 is a vertical section through the housing of the ball projecting apparatus, 60 illustrating the latter in detail, this view being taken along the line 6—6 of Fig. 7.

Fig. 7 is a side view of the same parts at right angles to Fig. 6.

Fig. 8 is an enlarged detail sectional view 65 illustrating particularly the iris adjusting means, this view being taken along the line 8—8 of Fig. 6.

Fig. 9 is a horizontal section taken along 70 the line 9—9 of Fig. 7.

Fig. 10 is a face view of the switchboard for controlling the lamps.

Fig. 11 is a bottom edge view thereof.

Fig. 12 is an enlarged fragmentary horizontal section on the line 12—12 of Fig. 10. 75

As here embodied my improved apparatus comprises, briefly, a board, or "screen," marked to represent the playing field or "diamond" and on which the pictures or representations are projected; a projector frame supporting a multiplicity of projection devices for showing the movements of those taking part in the game; an angularly adjustable projector for indicating the flight of the ball, and a switchboard for controlling the illumination of the projector lamps.

The board representing the playing field is indicated at 10 (Figs. 1 and 3) and may be of rectangular shape as shown, the positions of the various players being indicated by marks 11.

The projection frame is indicated generally at 14 in Fig. 1 and may be made up of a number of suitably arranged angle bars 95 15 forming supports for the projection devices. The board 10 and frame 14 are arranged in vertical position facing one another as shown in Fig. 1, being supported in any suitable manner. The angle bars 15 of the frame 14 are preferably arranged in the manner indicated in Fig. 2, extending generally speaking, along lines approximating the paths traveled by the players during the game, such as in walking to and from the bench or "dugout" and the home plate; traveling around the bases, or fielding batted balls.

These bars 15 support a multiplicity of projectors which are arranged to direct individual pictures upon the proper parts of the board, the pictures being shown in such 1.

sequence as may be desired to give an actual life-like representation of the players in movement. For instance a man running the bases can be shown by a series of pictures 5 directed in succession along the base lines and showing in proper sequence the different positions of the limbs assumed while running. In the same way a man can be shown chasing a batted ball. Likewise, by 10 directing a succession of pictures on the one spot, a man can be shown in the act of pitching, umpiring or coaching, or catching the ball, it being possible to show in complete detail the actions of all those taking part in 15 the game, the above noted instances being given for purposes of illustration.

The projectors are adapted to be mounted in closely spaced relation along these bars. These projection devices are indicated in detail 20 in Figs. 4 and 5 and comprise the base brackets 18 which are riveted or otherwise secured on the bars 15 and are formed with rearwardly projecting feet 18' adapted to support a lamphouse 19 in which is a lamp 20 having behind it the usual reflector 21. Located in front of the lamp 20 is a projector element comprising a tubular member 22 containing front and rear lenses and a picture plate 23. Since the manner of constructing these devices is well known a detail illustration thereof is not deemed necessary. The member 22 is preferably attached to the bracket 18, the latter having upwardly projecting studs 25 and 26, upon which the member rests, a single stud 25, curved to fit the circular surface of the member 22, being provided, while a pair of transversely spaced studs 26 are provided. A wire 22' engages over the member 22 to hold it on the bracket 40 18, the ends of the wire being secured to the bracket.

The projection devices just described are used for showing the representation of the players on the board, while for indicating 45 the flight of the ball I employ the device illustrated in detail in Figs. 6, 7 and 8.

This device as here embodied comprises a box 30 which may be mounted on a suitable support, such as the table 31, just behind the 50 frame 14. This box 30 is here shown as divided by a horizontal partition 32 into upper and lower compartments 33 and 34. In the upper compartment the projection means proper is located, while the lower compartment contains the control means therefor, the front of the box being open to accommodate the projection means, while the lower compartment is open at the adjacent side for the introduction of the operator's hand. 55

60 Within the box 30 a vertical shaft 35 is mounted, this shaft extending from a point adjacent the bottom of the box up through the partition 32. The shaft 35 is mounted between its ends in a universal joint 36 of

the ball type so as to permit both of rotary 65 movement and of swinging movement in any direction to positions other than vertical. The universal joint 36 is here shown as fixed on an arm 37 secured to the back of box 30, while the partition 32 is provided with a 70 suitable aperture to accommodate the shaft 35.

Upon the upper end of shaft 35 is mounted a tubular projection element 40 provided with a downward offset 41 at its rear end to 75 support the lamp 42 behind which is a reflector 43. The projector is provided with front and rear lenses 44 and 45. The former of these lenses is carried in a short tube 46 telescoping into the main tube 40, so as to 80 adjust the focus of the projector, the means for adjusting tube 46 being presently described in detail.

The representation of the ball is obtained by projecting a spot of light upon the board 85 10 through an iris 48 mounted on the projector. This iris may be of ordinary construction and detail illustration thereof is therefore not deemed necessary. In order to prevent the ball having the appearance of 90 increasing in size as the projector is swung at an oblique angle to the board to indicate the ball as traveling to different parts thereof, I have provided a means which automatically opens or contracts the iris 48 as 95 the projector is swung on its support 36 to different angles with respect to the board 10. Also, to maintain the proper focus of the lenses 44 and 45 as the distance between the projector and the point of the board on 100 which the beam of light strikes varies the tube 46 is provided with an adjusting means having an operative connection with the means for operating the iris 48 so as to be adjusted automatically in unison with the 105 latter.

To obtain the above noted adjustment of the iris 48 the operating element thereof is provided with four radially projecting arms 50 comprising a pair of diametrically opposed horizontal arms and a pair of diametrically opposed vertical arms. Each of these arms 50 has a pin 51 fixed to its outer end, these pins engaging in longitudinal slots 52 in the ends of abutment links 53, these links being connected at their opposite ends, by universal joints 54 which may be of the gimbal type, to the walls of the top compartment 33 of the box 30, each link extending at right angles to the arm iris with which it engages. When the projector is positioned at right angles to the board 10 the pins 51 are each at one end of their respective slots, being held in this position by a tension spring 55 connected to one of the 115 iris arms 50, and it will be apparent that no matter in what direction the projector may be swung one of the arms 50 will move the 120

iris by reason of the engagement of the pin thereon with the end of the slot into which it projects.

For adjusting the lens 44 as the projector 5 swings, the tube 46 carrying the lens has a spiral groove 58 formed in its periphery and engaged by a pin 59 carried by the tube 40, so that a rotation of said tube 46 will cause it to move axially. Upon the outer end of 10 said tube 46 a gear 60 is fixed and engages an elongated gear 61 fixed on a shaft 62 suitably journaled in a bracket 63 depending from the tube 40. Upon shaft 62 is fixed a pinion 64 engaging with a gear segment 65 15 formed on one of the iris arms 50. When the angle of the projector with respect to the board 10 is varied, the iris arms 50 will be operated, segment 65 rotating pinion 64 and in consequence gears 60 and 61 will be 20 rotated, and the consequent rotation of tube 46 will move it axially and so vary the focus of lens 44, the gears 60 and 61 maintaining engagement during such axial movement by reason of the elongated construction of gear 25 61.

In order to enable the operator to more readily direct the beam of light representing the ball in the proper directions and to the proper points on board 10 the bottom of 30 the box 30 is marked as indicated generally at 66 in Fig. 9 to represent the playing field and the lower end of shaft 35 has hinged thereto a pointer 67 pressed downward on said playing field by a spring 68, while the 35 shaft has fixed thereon a handwheel 69 adapted to be grasped by the operator in manipulating the projector. It will be understood that the parts will be so proportioned that movement of the pointer 67 along the bottom of box 30 will correspond to movement of the spot of light along the board 10.

The means for controlling the lamps 20 which serve the projectors on frame 14 is 45 illustrated particularly in Figs. 10, 11 and 12. This means comprises a panel board 75 which may be divided into three sections and provided with suitable switches controlling different set of the lamps 20.

The upper portion of the panel board has 50 three main series of control switches for indicating respectively the movement of the men on bases, and the infield and outfield of the opposing team. The first of these 55 comprises two concentric circular rows of switch points, indicated respectively at 76 and 77 mounted on said board. Adjacent the outer row 76 a switch ring 78 is rotatably mounted and carries a series of four 60 evenly spaced contact arms 79 which are adapted to project over the points 76. These arms are preferably adjustable radially on the ring 78 so as to be moved into and out of engagement with the points 76, the arms 65 being here shown as secured to the ring by

means of wing-headed screws 80 threaded into the ring 78 and passing through slots 82 in the arms 79. A suitable frictional hold is maintained on the arms 79 by means of bow springs such as 80' fixed to the arms 79, these springs being apertured to receive the screws 80. The arms 79 are adjusted by means of levers 79' hinged to the ring 78 and having the outer ends of the arms connected thereto. The projectors controlled 75 by the switch points 76 and arms 79 are directed upon the base lines of the diamond on board 10 so that the movement around the bases of the players of the team at bat may be shown by proper manipulation of 80 the ring 78. If one man is to be shown traveling on the bases only one of the arms 79 is left in engagement with the switch points 76, the number of arms in engagement with the switch points corresponding 85 to the number of men on bases, while the positions of the arms in use will be made to correspond with the positions of the men on bases.

The second of these main series comprises a number of radially arranged rows of switch points 82 at the ends of which are circumferentially offset points 83. These are controlled by a radial arm 84 slotted as at 85 to receive a longitudinally adjustable contact indicated generally at 86. The third of these comprises four concentric rows of switch points 89 one for each infield player, controlled by a switch arm 90 slotted as at 91 to adjustably hold a contact indicated generally at 92, this arm being hinged as at 93 to permit of its being lifted from contact with the switch points 89.

In addition to the above main series of switches I provide a series of switch points 95 controlled by a hinged switch arm 96, the lamps in this circuit controlling projectors indicating the movements of the batters, either right or left hand. I provide also two rows of switch points 97 and 98 controlled by hinged switch arms 99 and 100 adapted for operation when the movements of the catcher are to be shown, the upper row being used to indicate movements of the catcher in receiving or throwing a ball, and the lower row to show when the catcher walks up to consult with the pitcher. Also a series of switch points 101 controlled by a hinged arm 102 for showing the movements made by the umpires in declaring strikes or balls, the same arm being used to control a series of nine switch points 102' connected with projectors signaling which man is at bat. Also two rows of switch points 103 and 104 controlled by a single arm 105 are used in connection with showing the movement of the batter from the dugout to the plate and back again. Projectors are also provided to show the movement of the coaches at first and third

90

95

100

105

110

115

120

125

130

base, being controlled by the rows of switch points 106 and 107, and hinged switch arms 108 and 109. I also provide three series of switch points 110, controlled individually by arms 111 to show the number of strikes or balls served to a batter and the number of men out. These signals together with the names and playing positions of the men at bat may be thrown in a marked off space 10' on the board 10. Projectors showing the movements of the pitcher are controlled by the concentric arcuate rows of switch points 115 engaged by a hinged contact arm 116 slotted as at 117 to receive an adjustable contact member 118. I also provide a circularly arranged row of switch points 120, divided into four series and controlled by the switch arms 121 and 122, to indicate when a new pitcher is warming up and when a pitcher is taken out and the new one sent in.

It is not considered essential that a detailed description of the manner of use of my improved apparatus in the playing of a game be given. It will be apparent that by moving shaft 35 the spot of light representing the ball can be caused to move as desired on the board 10, while by proper manipulation of the various switch arms pictures showing the actions of the players can be thrown in proper sequence on the desired parts of said board.

Having thus described my invention what I claim as new and desire to protect by Letters Patent of the United States is as follows:—

1. In an apparatus of the type described, means for indicating the travel of a ball comprising a projector adapted to throw a beam of light upon a surface representing a playing field, a support for said projector, means for angularly adjusting said projector upon its support, and means operating in conjunction with said first means for varying the size of the spot-light aperture in the projector.

2. In an apparatus of the type described, means for indicating the travel of a ball comprising a projector adapted to throw a spot of light upon a surface representing a playing field and having an iris through which the light is projected, a support for said projector, means for angularly adjusting said projector on its support, and means for automatically opening and contracting said iris upon angular movement of said projector on its support.

3. In an apparatus of the type described, means for indicating the travel of a ball comprising a projector adapted to throw a spot of light upon a surface representing a playing field, and having a four-armed iris through which the light is projected, a support for said projector, means for angularly

adjusting the projector on its support, and devices adapted to engage the respective arms of said iris to automatically open or contract said iris upon angular movement of said projector on its support.

4. In an apparatus of the type described, means for indicating the travel of a ball comprising a projector adapted to throw a spot of light upon a surface representing a playing field, and having a four-armed iris through which the light is projected, a support for said projector, means for angularly adjusting the projector on its support, and devices adapted to engage the respective arms of said iris to automatically open or contract said iris upon angular movement of said projector on its support, said means including links having a slot and pin engagement with the arms of the iris.

5. In an apparatus of the type described, means for indicating the travel of a ball comprising a projector adapted to throw a spot of light upon a surface representing a playing field, and having a four-armed iris through which the light is projected, a support for said projector, means for angularly adjusting the projector on its support, and devices adapted to engage the respective arms of said iris to automatically open or contract said iris upon angular movement of said projector on its support, said means including links having a slot and pin engagement with the arms of the iris, said links being attached by a universal joint to a fixed part.

6. In an apparatus of the type described, means for indicating the travel of a ball comprising a projector adapted to throw a spot of light upon a surface representing a playing field, a support for said projector, means for angularly adjusting said projector upon its support, and means operating in conjunction with said first means for varying the focus of the projector, said last means including a tube axially movable on said projector, a lens in said tube, and means for imparting axial movement to said tube.

7. In an apparatus of the type described, means for indicating the travel of a ball comprising a projector adapted to throw a spot of light upon a surface representing a playing field, a support for said projector, means for angularly adjusting said projector upon its support, and means operating in conjunction with said first means for varying the focus of the projector, said last means including a tube in said projector having a spiral slot and pin connection therewith, a lens carried by said tube, and a gear on said tube for rotating the same.

8. In an apparatus of the type described, means for indicating the travel of a ball comprising a projector adapted to throw a spot of light upon a surface representing a

a playing field, a support for said projector, means for angularly adjusting said projector upon said support, and means for automatically adjusting the focus of the 5 reflector and the size of the spot-light aperture when the projector is moved angularly on its support.

9. In an apparatus of the type described, means for indicating the travel of a ball 10 comprising an angularly adjustable projector having an iris through which a spot-light is projected, a lens carrying tube axially movable in the projector by rotation of said tube, and means for automatically adjusting said iris and said tube upon angular 15 movement of said projector.

10. In an apparatus of the type described, means for indicating the travel of a ball 20 comprising an angularly adjustable projector having an iris through which a spot-light is projected, a lens carrying tube axially movable in the projector by rotation of said tube, and means for automatically adjusting said iris and said tube upon angular 25 movement of said projector, said means in-

cluding a series of radial arms on the iris, abutment elements engaged thereby, a gear segment on one of said arms, and an operative connection between said gear segment and tube to rotate the latter.

30

11. In an apparatus of the type described, means for indicating the travel of a ball comprising an angularly adjustable projector having an iris through which a spot-light is projected, a lens carrying tube 35 axially movable in the projector by rotation of said tube, and means for automatically adjusting said iris and said tube upon angular movement of said projector, said means including a series of radial arms on 40 the iris, abutment elements engaged thereby, a gear segment on one of said arms, and an operative connection between said gear segment and tube to rotate the latter, said operative connection including a gear fixed to 45 said tube, and an elongated gear meshing with said first gear.

In testimony whereof I have affixed my signature.

GEORGE S. COLEMAN.
